INTERNAL COMBUSTION ENGINE

Ross J. Sweeney, Harrisburg, Pa.

Application March 13, 1936, Serial No. 68,692

13 Claims. (Cl. 123—1)

This invention relates to improvements in reciprocating engines and more particularly to internal combustion engines of the piston reciprocating type; the present application is a continuation in part of my application Ser. No. 31,975, filed July 18, 1935.

An object of this invention is to provide new and improved means for increasing the efficiency of engines of the character stated by increasing the power, eliminating or reducing vibration, decreasing the fuel consumption, and permitting a considerable reduction of the gear ratio.

In the accompanying drawings which illustrate applications of my invention:

15 Fig. 1 is a diagrammatic view showing my invention applied to a four cylinder four cycle engine and illustrating the electrical circuit employed;

20 Fig. 2, a diagrammatic view illustrating the angular relation of the magnetic force to the engine cycles;

Fig. 3, a longitudinal section taken through an engine cylinder equipped with an electro-magnet in accordance with my invention;

25 Fig. 4, a view similar to Fig. 3, showing a modified form of magnet;

30 Fig. 5 a diagrammatic view of my invention, the view being similar to Fig. 1, showing a modified form of construction of the electro-magnetic means and its association with the pistons of a plurality of cylinders;

35 Fig. 6, a diagrammatic view illustrating the angular relationship of the magnetic forces to the engine cycles when magnetic means of the form of Fig. 5 are employed; and

Fig. 7, a longitudinal sectional view taken through a pair of engine cylinders equipped with the form of magnetic means illustrated in Fig. 5.

As illustrated, my invention is embodied in a 40 four cylinder four cycle internal combustion engine.

In the form of Fig. 1, which will be first described, 1, 2, 3, and 4 respectively designate the cylinders thereof in which reciprocating pistons 5, having a sheet or coating 6 of magnetic material are mounted in the usual manner; the pistons being connected with a crank shaft 7 by piston rods 8. It will of course be understood that the usual ports, valves and other operative parts employed in engines of this character are to be used, but as these elements form no part of the present invention and are well known to those skilled in this art, it is deemed unnecessary to show and describe them herein.

55 A characteristic and important feature of my

invention resides in the employment of electrical means associated with the engine and functioning to effect a pull or lift on one or more pistons of the engine whereby, in conjunction with the power derived from the explosive mixture, approximately 5 continuous application of power to the crank shaft of the engine is provided. Another important feature is, that a smoothness of operation and lack of vibration is produced.

The electrical means I prefer to employ comprise 10 electro-magnets preferably mounted on the cylinder head or heads of the engine and connected with a suitable source of electric current as a storage battery or a generator.

Referring to Fig. 1, each of the cylinders 1, 2, 3, 15 and 4 is provided with an overhead electro-magnet 9 comprising a central soft iron core wound in the usual manner, said cores extending through the cylinder heads for internally establishing a magnetic flux or magnetic lines of force within 20 said cylinders.

The electro-magnets are electrically connected in any suitable circuit with a battery 10 or other source of electrical energy. As shown, one lead of each of the magnets is connected by a common 25 wire 11 with one side of the battery, said battery being grounded on its other side as at 12. The other leads of the magnets are connected with contacting devices 13 and 14 located on and rotatable with the crank shaft 7. 30

As is well known, the usual crank shaft of a four cylinder four cycle engine is arranged to actuate the pistons in pairs, as for example in Fig. 1, the pistons of cylinder 1 and 3 operate together, and the pistons of cylinders 2 and 4 35 move together, each pair moving in relatively opposite directions.

For the purpose of applying a magnetic force on the up-strokes of the pistons, i. e., the compression and exhaust strokes, the electro-magnets 40 of cylinders 1 and 3 may be energized at the same time, and those of cylinders 2 and 4 together at an interval from the energization of those of cylinders 1 and 3.

In order to automatically effect the energizing 45 and de-energizing of the said pairs of electro-magnets I employ (in the form of Fig. 1) means including a commutator. The leads of the electro-magnets of cylinders 1 and 3 are connected by a wire 15 with a brush or contact point 16 50 on the rotating commutator 13, and the leads of electro-magnets of cylinders 2 and 4 are connected by a wire 17 with a brush or contact point 18 on the commutator 14.

The commutators comprise segmental insulat-

ing sections 19 and segmental conductors 20, the conductors 20 being angularly located 180 degrees apart and in contact with the metal of the crank shaft 7, which shaft is in turn ground-
ed as at 21.

Commutator conductor segments 20 are related to the angular travel of the crank shaft and the corresponding linear movement of the pistons, so that an electrical circuit is made through 10 the magnets during the upward or compression and exhaust strokes of the respective pistons, the angular duration of the magnetic force being indicated in Fig. 2.

In other words, the magnetic force set up by 15 the electro-magnets is applied to the respective pistons as they approach upper side center positions, and is continuously applied with increasing lifting effect as the pistons approach upper dead center, being terminated slightly in advance 20 of ignition as indicated at *a* in Fig. 2, so as to have no retarding effect upon the power stroke.

It will be understood that a manually controlled switch *b*, may if desired, be placed in the line 11 and controlled from any convenient point.

25 As illustrated and as preferred the electro-magnets each have an outside diameter less than the internal diameter of the cylinder over which the electro-magnet is mounted. As shown, each electro-magnet proper is disposed within a housing 21 made of some suitable non-magnetic material or materials with a fixed core 22 of the magnet projecting through the housing and entered in and extending through the cylinder head 23. 24 designates a non-magnetic locking nut 30 internally threaded to receive the threaded portion 25 of the core, and 26 a non-magnetic bushing disposed and maintained in the cylinder head and adapted to receive the lower portion of the core 22.

40 Core 22 is preferably formed with an enlargement 27 at its inner end and bevelled as shown to contact with a bevelled face of the bushing 26.

In the form of Fig. 4, I have shown a modified form of electro-magnet, in this instance two cores 45 22a are employed and extend through non-magnetic bushings 26a, the latter being entered in the cylinder head 23a.

In the form of Figs. 5 and 7, in place of the fixed core type of electro-magnets, I employ a 50 movable core or plunger type of magnet.

Referring now to the embodiment of my invention employing the said movable core type of electro-magnet, said magnets are adapted to be positioned on each of the cylinders 1', 2', 3', and 55 4' in which reciprocating pistons 5' are mounted and operable in the usual manner; the pistons being connected with a crank shaft 7' by piston rods 8'. The respective magnets are, as in the former described embodiments, connected 60 with a suitable source of electric current, as a storage battery or a generator.

The electro-magnets designated generally by the numeral 9' include a centrally disposed movable plunger or core 22' designed to be movable 65 within the magnet. The plunger or core 22' for most of its length is made of a suitable magnetic material of such length as is required by the stroke of the engine, said core 22' being of sufficient length to project through the head of 70 the cylinder to which it is applied and be connected by suitable means to the piston head 5'.

The energization and the de-energization of this form of magnet may be effected by means of the commutators as heretofore described in connection with the fixed core type electro-mag-

nets, or in place of the last mentioned energizing and de-energizing means a different form of switch mechanism, as particularly shown by Fig. 7, may be utilized. When this last mentioned form of switch mechanism is employed the movable core or plunger adjacent its top or an end thereof is preferably provided with a non-magnetic and non-conducting terminal 28. The employment of this terminal makes the pull or lift more effective as the movable core nears the top 10 or an end of the solenoid or magnet and further functions to make a non-conducting contact with the switch mechanism illustrated by Fig. 7.

The movable core or plunger is designed to move through the cylinder head in a non-magnetic bushing 29 made of brass or some other suitable material of low magnetic permeability and of a construction adapted to receive a plurality of compression rings 30. These compression rings 30 disposed in the bushing are preferably made of brass or some other non-magnetic material and are designed to prevent any magnetic and/or compression leakage at this point. I prefer to form the bushing 29 and the central tubular member 31 of the magnet, from a single 25 piece of metal; this construction may be utilized for receiving oil to lubricate the compression rings. As shown the plunger 22' has a suitable clearance within the tubular member 31.

The switch mechanisms as illustrated, include 30 a horizontally disposed member 32 formed of good conductive material, and of sufficient length to bridge a pair of cylinders of the engine; this member is pivotally mounted across the upper ends of the associated magnets 9' on a support 35 33, and is provided with spaced apart adjustable electric contacts 34 for contacting with points 35, the latter being carried on the magnets and connected with the windings thereof. The switch member is further provided with spaced apart 40 adjustable insulator blocks 36 adapted to be engaged by the insulated ends of the cores 22' as said cores complete their up-strokes. 37 designates adjustable magnetic blocks also carried by the member 32 above and in line with each mag- 45 net.

As shown in Fig. 5, the electro-magnets 9' are connected in circuit with a battery 10' or other source of electrical energy through the switches 32. One lead of each magnet connects with its 50 contact point 35, and the other lead connects with a common conductor 38 which latter wire is grounded at 39. The switches 32, and therefore their points 34, are connected through a common wire 40 with one side of the battery 10', said bat- 55 tery having its other side grounded at 41.

For the purpose of illustration, the pistons 5' and crank shaft 7' are shown in dead center position. Thus, the pistons of cylinders 1' and 3' have reached their upper limit of travel, and the 60 terminal ends of their cores 22' have tilted the switch members 32 to make contact between their points 34 and points 35 of the electro-magnets on cylinders 2' and 4', thereby energizing 65 said electro-magnets during the following upward strokes of the pistons in said cylinders 2' and 4'.

It will readily be seen, that upon the completion of the cycle illustrated, as determined by a complete stroke of the pistons, the cores 22' of 70 the pistons in cylinders 2' and 4' will oppositely tilt the switches 32 for energizing the electro-magnets 9' of cylinders 1' and 3', at the same time de-energizing the magnets of cylinders 2' and 4'. In this manner, the movement of the

pistons and particularly their connected cores 22', will alternately make and break the switch and magnet contacts to energize and de-energize the magnets of the pairs of cylinders, so as to 5 always exert a magnetic force upon the pistons during their upward travel, or more particularly, during the compression and exhaust strokes thereof.

While the electro-magnets are respectively energized as the pistons of their associated cylinders reach lower dead center position, I prefer to delay the application of the resulting magnetic force to the movable cores 22' until the pistons have traversed the dead center position, thereby 15 eliminating the possibility of any undesirable tendency to reversal of rotation of the motor.

For this purpose, I provide the non-magnetic terminals 28 of the cores 22' of sufficient length, relative to the length of the piston stroke and to 20 the height of the magnets 9', so that the said cores are effectively insulated against magnetic action until the pistons have passed dead center, or until such interval of motion beyond dead center advances the said non-magnetic terminals 25 of the respective upwardly moving cores within their magnets so as to bring the magnetic portions of the cores into the magnetic fields of said magnets. This interval is indicated at c in the diagram of Fig. 6.

30 Adjustment of the switches may be made with a high degree of accuracy by means of the adjustable contacts 34 and adjustable blocks 36. I have also provided means to secure the switches against accidental disengagement when in contact, the magnetic blocks 37 being attracted to the respective magnets being energized, thereby maintaining the switches in tilted contact position until displaced by the terminal of a movable core, as described.

40 By means of the movable core construction described, I am enabled to obtain maximum efficiency in the application of magnetic force to the pistons of an engine. Thus, as shown in Fig. 6, the magnetic force may be continuously applied from an interval c slightly beyond lower dead center position to a point slightly in advance of ignition, as indicated at a, during the upward or exhaust or compression strokes of the piston.

50 The magnetic force so exerted on the movable cores, and therefore their pistons, will increase in magnitude with the travel of the piston. I have found that the maximum effort is obtained when the piston has travelled substantially three-fifths of the length of its stroke. Likewise, there 55 is an attendant decrease in amperage from a maximum at the start of the stroke to a minimum at the end thereof, both of which limits have been found to be well within the capacities 60 of the usual generator and storage battery equipment commonly employed in automotive vehicles.

The employment of either form of electro-magnet in connection with an internal combustion engine in the manner shown and described 65 herein results in increasing the power of the engine, eliminates vibration, produces a smooth running engine, effects a considerable saving by decreasing the fuel consumption, and permits a considerable reduction in gear ratio.

70 I claim:

1. In combination in an internal combustion engine, of a cylinder and a power piston operable therein, energizing electrical means associated with the piston, and means for automatically energizing said means to effect a pull on the piston

during the compression and exhaust strokes of the engine.

2. In combination in an internal combustion engine, of a cylinder and a power piston operable therein energizing electrical means associated with the piston and means for automatically energizing said means to effect a pull on the piston during the compression and exhaust strokes of the engine and de-energizing said means during the intake and firing strokes of the engine. 10

3. In combination with a four cycle internal combustion engine, of a cylinder and its head and a power piston operable in the cylinder, an electro-magnet mounted on the head, and means for energizing the electro-magnet for effecting a 15 pull on the piston during the compression stroke of the engine.

4. In combination with a four cycle internal combustion engine, of a cylinder and its head and a power piston operable in the cylinder, an electro-magnet mounted on the head, and means for energizing the electro-magnet for effecting a 20 pull on the piston during the exhaust stroke of the engine.

5. In combination with a four cycle internal combustion engine, of a cylinder and its head and a power piston operable in the cylinder, an electro-magnet mounted on the head, and means for energizing the electro-magnet for effecting a 25 pull on the piston during the compression and exhaust strokes of the engine and de-energizing the electro-magnet during the intake and firing strokes of the engine.

6. The combination in an internal combustion engine, of a cylinder and a power piston operable therein, electro-magnetic means on the cylinder having a core extending beyond the winding and through a wall of said cylinder, non-magnetic means coating with the extension of the core 30 detachably securing it in said wall, means for periodically energizing the electro-magnet, during the compression and exhaust strokes of the engine and de-energizing the electro-magnet during the intake and firing strokes of the engine. 45

7. The combination in an internal combustion engine, of a cylinder and a power piston operable therein, an electro-magnet on the cylinder having a core extending beyond the winding and through a wall of said cylinder, an enlargement on the 50 inner end of said core, a non-magnetic bushing surrounding the extension of the core and forming a seat at one end for said enlargement, said bushing being screw threaded in the cylinder wall, a non-magnetic nut screw threaded to the 55 extension of the core and engaging the other end of the bushing, means for periodically energizing the electro-magnet, during the compression and exhaust stroke of the piston, said piston being in the field of said electro-magnetic means 60 during said compression and exhaust stroke.

8. In combination with an internal combustion engine having a plurality of cylinders affording combustion chambers and power pistons in said chambers operable by the explosions therein, a shaft, means to operate said shaft from said pistons, an electro-magnet on each cylinder, each piston being in the field of the associated electro-magnet during the exhaust stroke, a source of 65 electrical energy having one terminal grounded to the engine and a conductor extending from the other terminal to each electro-magnet, commutator means on said shaft, and conductors one for each magnet controlled by said commutator 70

means according to the order of exhaustion of the cylinders.

9. The combination in an internal combustion engine, of a cylinder and a power piston operable therein, an electro-magnet on the cylinder having a movable core extending beyond the winding through a wall of the cylinder and connected with the piston, means for energizing the electro-magnet to effect a pull on the piston during the compression stroke.
10. In combination in an internal combustion engine, of a cylinder and a power piston operable therein, electro-magnetic means including a movable core associated with the piston, means operable by the core for energizing the electro-magnetic means to effect a pull on the piston during the compression and exhaust strokes of the engine and de-energizing said means during the intake and firing strokes of the engine.
11. In combination with an internal combustion engine having a plurality of cylinders affording combustion chambers and power pistons in said chambers operable by the explosions

therein, an electro-magnet on each cylinder including a movable core connecting the piston thereof, a source of electrical energy, a switch mechanism associated with two cylinders operable by a movement of the cores to alternately energize the respective electro-magnets.

12. The combination in an internal combustion engine, of a cylinder and a power piston operable by explosions therein, an electro-magnet having a movable core extending through a wall of the cylinder and connected with the piston, and means for energizing the electro-magnet during the exhaust stroke of the engine to effect a pull on the piston.

13. The combination in an internal combustion engine, of a cylinder and a power piston operable by explosions therein, an electro-magnet having a movable core extending through a wall of the cylinder and connected with the piston, and means for energizing the electro-magnet during the compression stroke of the engine to effect a pull on the piston.

ROSS J. SWEENEY.
